UNITED STATES PATENT OFFICE.

CHARLES FRANCIS JENKINS, OF WASHINGTON, DISTRICT OF COLUMBIA.

MOTION-PICTURE CAMERA.

1,089,646.

Specification of Letters Patent. Patented Mar. 10, 1914.

Application filed June 27, 1912. Serial No. 706,187.

To all whom it may concern:

Be it known that I, CHARLES FRANCIS JENKINS, citizen of the United States, residing at Washington, in the District of Columbia, have invented certain new and useful Improvements in Motion-Picture Cameras, of which the following is a specification, reference being had therein to the accompanying drawing.

10 My invention relates to motion picture cameras in which the sensitized film is continuously withdrawn from a light tight box, exposed, and rewound in a similar box in the horizontal plane of the box first mentioned, the exposure being made in the axial line of a lens continuously moving in a circular path in a plane perpendicular to the plane of the exposed portion of the film, and light being admitted at intervals determined by a 20 rotary shutter.

In the accompanying drawings, Figure 1 is a plan view of the apparatus, the top of the camera box or casing being removed. Fig. 2 is a side elevation of the same devices, 25 the side of the casing nearest the observer being removed. Fig. 3 shows the same apparatus as seen from the left in Fig. 2, the end of the casing being removed. Fig. 4 is a plan view of a lens and film-guide carrying box. Fig. 5 is a view of the front end of the box of Fig. 4. Fig. 6 is a side elevation of the same box. Fig. 7 is a detail sectional plan view of a portion of the film winding devices.

30 In these figures, A represents a casing having a door A', a front light-aperture A², a transverse partition A³, and a partial longitudinal partition A⁴ rigidly fixed to the partition A³ and with it detachably fixed to the casing by screws, so that both partitions and most of the working parts, carried thereby, may be removed as a whole from the casing. B, B' represent two removable light tight film boxes resting on the rear 40 portion of the bottom of the casing and in opposite corners of the latter. In the rear of the partition A³ is a box C from which a lens tube C' projects through an opening, in the partition, adapted to permit the tube to move in a vertical circular path, light being excluded in a suitable way, shown in this instance as by means of a thin flexible diaphragm C² connecting the front end of the box and the margins of the opening in the partition. The box C is fixed to a link D the ends of which are carried in equal

50 circular paths by crank-plates D', D², the former driven from a power shaft E by means of gears F, F', F², and the latter driven at the same speed by the gear F and gears F³, F⁴, the box being thus moved bodily in a vertical circle the diameter of which is equal to that of the circle described by either crank pin.

55 Between the lens tube and the front wall of the casing is a rotary shutter G driven from the main shaft E by gears G', G² and a shaft G³.

Film, H, is drawn forward from the box B, passed around a direction charging rod I, inclined with respect to the film's adjacent path then rearwardly around similar rods I', under rollers I², I³, to a sprocket drum J, which constantly feeds it forward and against which it is pressed by the roller last 75 mentioned. From the drum, it passes forward and then downward under a spring-pressed guide plate K, on the rear end of the box C, around a roller L, and thence back to the lower side of the drum, against which it 80 is held by a roller L'. From the drum, it passes around rollers M, N to the other film box B', where it is wound into a roll, upon a hollow spool O detachably fixed to a short shaft O' mounted in a sleeve bearing O² 85 carried by a plate O³ fixed to the wall of the box B', the shaft being provided at its outer end with a crossbar O⁴ lying in a recess in the box wall.

To the rear vertical margin of the partition A⁴, a broad arm or frame P, in the plane of the partition, is hinged to swing toward the door of the casing but not oppositely. In the rear free end of that arm is mounted a short shaft Q having, on one 90 side of the arm a pulley Q', and upon the other side, next the box B' a fork Q² adapted to pass freely into and out of engagement with the crossbar O⁴ when the box is moved laterally into and out of normal position. 100 The pulley Q' is driven by a preferably elastic belt R from a pulley R' on the main shaft E.

To remove the boxes, the door being open, the film winding box B' is withdrawn horizontally, the crossbar on the winding shaft passing freely out of engagement with the fork Q², the hinged arm is swung on its vertical axis out of the path of the rear box B, and the latter is then removed like the 110 first. By this arrangement the boxes are conveniently handled although side by side

in the casing, and boxes large enough to contain very long films may be employed in a camera having no greater dimensions than are required for the other mechanisms, or in other words a casing in which only short films may be used ordinarily, answers for films of double the usual length.

In using the camera, the film is put in place and the crank is rotated, imparting movement to the various parts. The rotating drum constantly draws film from the box B and delivers it to the film guide and at the same time its lower side advances the film which has passed the guide. The box C meantime is moved in a circular path and as it rises and moves forward the drum holds the film on its lower side and hence the film slips under the guide K. As the box movement continues, the film becomes slack below the guide while owing to slack above there is no pull upon it in an upward direction and consequently it temporarily moves with the box and without movement with respect thereto. During this interval, the rotating shutter momentarily admits light and a picture is formed upon the portion of the film exposed at the rear of the box C and held by the guide. When the box has passed its lowest point and is rising, the movement aided by the action of the drum quickly takes up the slack below the guide and the forward movement of the box again draws the film down a picture's width.

What I claim is:

- 35 1. In motion picture apparatus, the combination with a lens and a film guide arranged to hold transversely disposed film at a constant distance from the lens, of means for moving the lens and guide together in a circular path, and means whereby the film is at intervals prevented from moving with the guide in a direction opposite to the direction of the film's feeding movement at the guide, whereby the film is caused to advance intermittently with respect to the guide.
- 50 2. In moving picture apparatus, the combination with a lens and a film guide adapted to hold a film strip at a constant distance from the lens, of means for moving the lens and film guide together in an endless path, means for causing the film to advance step by step in said guide, and means for interrupting the passage of light to the film while it is in motion.
- 55 3. The combination with means for constantly feeding a film strip, of a lens and a film guide, in fixed relation thereto, slightly resisting the advance of the film, means for moving the lens and guide together in an

endless path varying in distance from the constantly feeding means, and means for alternately allowing and interrupting the passage of light to the guided portion of the film said feeding means and means for 65 moving the guide being arranged to produce step by step advance of the film with respect to the guide, substantially as set forth.

4. The combination with a lens and a guide for frictionally holding film to be 70 fed transversely to the axis of the lens, of means for moving the lens and guide synchronously in an endless path, means whereby the film is at intervals prevented from moving with the guide in a direction opposite to the direction of the film's feeding movement at the guide, causing the film to advance with respect to the latter, and means for interrupting the passage of light to the guided portion of the film while the film is 75 80 thus advancing.

5. In motion picture apparatus, the combination with a lens moving in an endless path and carrying with it and in its axis a portion of a film, of means whereby said portion is exposed while the lens moves through a portion of its path, and means whereby the movement of the lens through another portion of said path brings a fresh portion of the film into said axis. 90

6. The combination with a camera casing, of continuously moving film feeding devices within the casing, constantly moving light interrupting devices, a removable box for unexposed film, a second removable box, 95 for exposed film, provided with winding devices, and a flexible arm extending alongside the second box and carrying actuating mechanism adapted to detachably engage the winding devices. 100

7. The combination with a camera casing provided with a lateral opening for the insertion and removal of film boxes, of two removable film boxes located side by side, in the same horizontal plane, within the casing, one of the boxes being provided with film winding devices, and an arm hinged to swing into and out of the path followed by one of the boxes in removal and provided with actuating devices adapted to engage 105 and disengage the winding devices as the arm and box pass into and out of normal positions.

In testimony whereof I affix my signature in presence of two witnesses.

CHARLES FRANCIS JENKINS.
